Primary Examiner — Janice Seeger*Assistant Examiner* — Martie K Holtje(74) *Attorney, Agent, or Firm* — Frank A. Lukasik(57) **CLAIM**

The ornamental design for a stealth origami airplane, as shown and described.

DESCRIPTION

FIG. 1. is a perspective view of a stealth origami airplane showing my new design.

FIG. 2. is a front elevational view thereof.

FIG. 3. is a rear elevational view thereof.

FIG. 4. is a right side elevational view thereof.

FIG. 5. is a top plan view thereof; and,

FIG. 6. is a bottom plan view thereof.

The broken lines shown in the drawing represent fold lines.
